UNITED STATES PATENT OFFICE

AARON ROSENSTEIN, OF NEW YORK, N. Y.

DESIGN FOR A TEXTILE FABRIC

Application filed August 20, 1932. Serial No. 44,654. Term of patent 7 years.

To all whom it may concern:

Be it known that I, AARON ROSENSTEIN, a citizen of the United States, residing at New York, county of New York, and State of New York, have invented a new, original, and ornamental Design for a Textile Fabric, of which the following is a specification, reference being had to the accompanying drawing, forming part thereof.

The figure is a plan view of a textile fabric showing my new design.

The dot and dash lines in the drawing outline the design unit, which unit is repeated in regular succession, as indicated by the extensions beyond the unit boundaries.

I claim:

The ornamental design for a textile fabric substantially as shown and described.

AARON ROSENSTEIN.
